(57) **CLAIM**

The ornamental design for a dental aspiration device, as shown and described.

DESCRIPTION

FIG. 1 is a perspective view of a dental aspiration device; FIG. 2 is a front view of the dental aspiration device; FIG. 3 is a back view of the dental aspiration device; FIG. 4 is a right elevational view of the dental aspiration device; FIG. 5 is a left elevational view of the dental aspiration device; FIG. 6 is a top plan view of the dental aspiration device; and, FIG. 7 is a bottom plan view of the dental aspiration device. The broken lines shown in the figures represent portions of the dental aspiration device that form no part of the claimed design.
